UNITED STATES PATENT OFFICE

CLIFFORD D. FALLERT, OF ST. LOUIS, MISSOURI, ASSIGNOR TO ROBERT GAYLORD
INCORPORATED, A CORPORATION OF MISSOURI

DISPLAY STAND

Application filed January 2, 1932. Serial No. 584,365.

My invention relates to a display stand and particularly to a stand which is formed of bendable sheet material, such as fiberboard, either solid or cellular.

5 The object of my invention is to produce a display stand which is simple in construction and easily assembled while being rigid and attractive in appearance.

In the accompanying drawing, which 10 illustrates one form of stand made in accordance with my invention, Figure 1 is a front elevation; Figure 2 is partly a top plan view and partly a section taken on the line 2—2 of Figure 1; Figure 3 is a section taken on the 15 line 3—3 of Figure 1; Figure 4 is a section taken on the line 4—4 of Figure 2; Figure 5 is a plan view of the blank from which the body of the stand is formed; and Figure 6 is a plan view of the blank from which the top 20 shelf member is formed.

For convenience in illustration I have shown the stand as formed of solid fiberboard, cellular board, such as single wall corrugated board will, however, be more suitable on account of its combined lightness and strength. The stand comprises a body portion and upper and lower shelf members. The body portion is formed from a blank, shown in Figure 5, consisting of a rectangular sheet of fiberboard. This blank is divided by vertical crease lines 1 into eight panels 2 which form the sides of an octagonal tubular member when the ends of the blank are secured together by any suitable means, such as a strip of gummed tape 3. Formed in alternate panels near the top of the blank are slits providing partially detached tabs 4 which may be bent inwardly at right angles to the panels to form integral supporting brackets for the top shelf member. Formed in alternate panels, preferably those situated between the panels in which the tabs 4 are formed, are slits providing partially detached tabs 5 which may be bent inwardly at right angles to the panels to form integral supporting brackets for supporting the lower shelf. The tabs 5 are of relatively large size so that the apertures formed when they are bent inwardly provide door ways through 50 which merchandise may be placed upon or

removed from the lower shelf. In the drawing I have shown the tabs 5 as extending entirely across the panels in which they are formed, except that the tab adjacent the end of the blank is somewhat narrower in 55 order to leave a connecting strip 6 to which the tape 3 may be attached.

The upper shelf consists of an octagonal piece of fiberboard 7 integral with one side of which is a display board 8, a crease line 9 being provided at the juncture of the two parts so that they may be bent at right angles to each other. The lower part of the display board is of a width not greater than that of one of the panels 2 but the upper part is made wider so that its lower edge may engage with slots 10 in the body portion which thus holds the display board in upright position. The lower shelf 11, formed of an octagonal piece of board, is similar to the shelf 7 but without the attached display board.

To assemble the stand, after the ends of the body blank are secured together, the tabs 5 are bent inwardly and the shelf member 11 inserted through the top of the body to rest thereon. The tabs 4 are now bent inwardly and the upper shelf 7 placed thereon, the lower edges of the enlarged portion of the display board engaging the slots 10, so that this board is firmly held in upright position 60 in order to not only provide a surface for advertising matter but also to serve as a support for tall articles displayed on the shelf 7. The contact of the edges of the shelves with the inner surface of the tubular body, 65 rigidly braces the walls of the stand against relative movement and thus produces a rigid structure in a simple and economic manner. This result might be obtained by so shaping the shelves that each would contact with only 70 alternate panels, but I prefer to form the shelves as shown so that each will contact with all eight panels.

Having fully described my invention, what I claim as new and desire to secure by Letters Patent of the United States is:

1. A display stand comprising panels forming an open end tubular body portion, two of said panels being provided with open ended slots positioned adjacent their junc-

tion with a third panel, inwardly projecting integral brackets carried by said body portion, a shelf capable of being introduced into the open end of the body portion, said shelf 5 resting upon said brackets, and a flange carried on one edge of said shelf and having laterally projecting parts entering the open ended slots when the shelf is positioned, whereby the shelf is held in position on the 10 brackets.

2. A display stand comprising panels forming an octagonal tubular body portion, inwardly projecting integral brackets carried by four alternate panels, a shelf supported on said brackets, door ways formed in the panels intermediate the panels carrying said brackets, the material detached to form said door ways being bent inwardly to form a second set of brackets below said first 20 named set, and a second shelf supported on

said second set of brackets adjacent the door ways.

3. A display stand formed from a rectangular blank divided by crease lines into eight panels, the free edges of the blank being joined to form an octagonal tubular member, supporting brackets adjacent the upper end of the stand formed by partially detached tabs formed from alternate panels, two panels being provided with open ended slots positioned adjacent their junction with a third panel, and a shelf provided on one edge with a flange, said shelf being supported on said brackets and the flange engaging with the slots to hold the shelf in position on the 75 brackets.

In testimony whereof, I hereunto affix my signature, this 29th day of December, 1931.

CLIFFORD D. FALLERT.
